UNITED STATES PATENT OFFICE.

EARLE J. R. BEATTEY, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

ATTACHMENT FOR SPECTACLE

1,293,671.

Specification of Letters Patent. Patented Feb. 11, 1919.

Application filed May 25, 1918. Serial No. 99,911.

To all whom it may concern:

Be it known that I, EARLE J. R. BEATTEY, citizen of the United States, and resident of the city of Providence, in the county of Providence and State of Rhode Island, have invented certain new and useful Improvements in Attachments for Spectacles, of which the following is a specification.

This invention relates to means for securing together the parts of eye-glass frames, spectacles or goggles and has for its primary object to provide a metal clamping member having bendable arms adapted to be wrapped about a non-metallic eye-glass frame for the purpose of securing together the abutting ends of the frame and also to provide simple, inexpensive yet a strong and reliable member to which the other parts of the spectacle or eye-glass frame may be connected.

A further object of this invention is the provision of means on the engaging surface of the clamp member for penetrating and bedding itself into the non-metallic frame to prevent relative movement of the parts after the clamp has been positioned.

With these and other objects in view, the invention consists of certain novel features of construction, as will be more fully described, and particularly pointed out in the appended claim.

In the accompanying drawings:

Figure 1— is a perspective view showing a pair of spectacles having non-metallic frames to which my improved clamp is shown as being attached.

Fig. 2— is a perspective view showing the sole form of clamp member as made all in one piece.

Fig. 3— is a perspective view showing the outer surface of this clamp as corrugated transversely.

Fig. 4— is a view of the clamp member showing the same as being provided with a row of spurs adapted to enter the surface of the frame to prevent slipping of the parts showing the engaging surface as corrugated.

Fig. 5— is a modification showing the clamp member as being provided with a plurality of engaging arms at each end.

Fig. 6— is an edge view of the frame in section showing the clamp member applied thereto.

Fig. 7— is a sectional view of the frame

just beyond the end of the clamp member shown in Fig. 6.

Fig. 8— is an edge view of the frame with the divided clamp member secured thereto and arranged to draw the ends of the frame together about the lens.

Referring to the drawings, 10 designates the frame portion of the eye-glass or that portion which encircles and incloses the lens 11. In forming these frames they are preferably constructed from a finished rod of celluloid, zylonite or other suitable non-metallic material. This rod is provided with a longitudinal groove 12, see Figs. 6 and 7, and is cut of a length to encircle the lens. The abutting ends 13 must then be provided with means whereby they may be drawn and fastened together about the lens.

To accomplish this in a simple and practical way, I have provided a clamp or clip 15 of metal which is formed of a thin elongated body portion 16 having a pair of laterally extending arms 17 at opposite ends of this body portion, said arms being of a length to be wrapped or folded about the frame, their extremities extending to the lens.

When applying this clamp to the side of the lens frame where the ends abut, I preferably form the body portion of the clamp in two parts as best illustrated in Figs. 1 and 8 and to each of these parts I have attached one half of a joint member 25 and pass a binding screw 20 through both of these halves, whereby when the screw is withdrawn the frame may be sprung open sufficiently to permit the ready insertion of the lens therein, and then by setting up the screw the frame is bound tightly about the lens.

These two half joint members 25 may be shaped so that the usual temple 21 may be pivotally mounted between them if desired or when the frame is used without the temple these joint members 25 may be made only just large enough to receive the screw and then used exclusively for joining the ends of the frame together.

In some cases the clamp may be made all in one piece as illustrated in Figs. 2 to 6 inclusive when it is desired to attach the bridge member 14 to the inner edge of the frame, see Fig. 1, in which case the body portion 16 of the clip is provided with a small hole 18 through its center portion into

which the ends of the bridge member are passed and riveted thereby providing a rigid support for the same.

A feature of my invention is that the inner surface 22 of the clip is toothed, corrugated or otherwise roughened, see Figs. 3 and 4, whereby when applied to the frame with pressure these corrugations embed themselves into the comparatively soft surface 10 face of the frame which effectually prevents slipping of the parts from the grasp or grip of the clip.

To further insure a positive gripping or clamping action on the frame, I have provided a spur 23, see Fig. 4, on opposite ends of the clamp which spurs are turned inward as illustrated in Fig. 7 so that when the clamp is applied to the frame it is forced into the relatively soft material and effectually locks the parts together.

A modified form of clamp or grip is illustrated in Fig. 5 in which a plurality of transverse arms 24 are attached to the body portion which are wrapped about the frame.

Having thus described my invention, I desire it to be understood that although specific terms are employed, they are used in a generic sense and are not for the purpose of limitation, the scope of the invention being defined and limited only by the appended claim.

I claim:

The combination with a non-metallic eyeglass frame, of a metal clamp for connecting together the parts of the frame, said clamp comprising a narrow body portion provided with a pair of laterally extending bendable arms at each end adapted to be wrapped about said frame, the engaging surface of said clamp being grooved laterally to engage the surface of the frame to prevent relative movement of the parts when connected thereto.

In testimony whereof I affix my signature in presence of a witness.

EARLE J. R. BEATTEY.

Witness:

HOWARD E. BARLOW.
